CLAIM

The ornamental design for a handheld grater, as shown, and described.

DESCRIPTION

FIG. 1 is a perspective view of a handheld grater;

FIG. 2 is a front elevation view thereof;

FIG. 3 is a rear elevation view thereof;

FIG. 4 is a right side view thereof;

FIG. 5 is a left side view thereof;

FIG. 6 is a top plan view thereof; and,

7 is a bottom plan view thereof.

The broken lines represent unclaimed matter and form no part of the claimed design.
